CLAIM

The ornamental design for a residential water well pump pulley, as shown and described.

DESCRIPTION

FIG. 1 is a side elevational view of a residential water well pump pulley showing my new design;

FIGS. 2 and 3 are respectively front and rear elevational views thereof;

FIG. 4 is the side elevational view opposite to FIG. 1;

FIGS. 5 and 6 are respectively bottom and top plan views thereof.

FIG. 5

FIG. 6

FIG. 4
